HEAT EXCHANGER

Clarence A. Quillen, Indianapolis, Ind.

Application November 15, 1940, Serial No. 365,751

1 Claim. (Cl. 285—210)

This invention relates to a heat exchanger of the tubular type, and it is a primary object to form permanent joints or seals at each end of a metal tube into which other tubes are carried, all without having to employ separate castings or fittings for the purpose.

An important advantage of the invention is found in the fact that not only is there a great saving in cost of material by elimination of fittings but also there is a considerable reduction in the labor cost of assembling and forming the seals. A further very important advantage is that a seal is formed at once in such a manner that there is no danger of melting or destroying other parts of a seal as has heretofore been the case when a fitting was employed requiring the brazing or sweating in one part in one step and a subsequent like operation in a second step wherein the heat required was likely to open up the seal formed in the first instance.

These and other objects and advantages of the invention will become apparent to those versed in the art in the following description of one particular form of the invention as illustrated in the accompanying drawing, in which

Fig. 1 is a side view in partial section of a structure embodying the invention;

Fig. 2, a view in transverse section on the line 2—2 in Fig. 1;

Fig. 3, a view in transverse section on the line 3—3 in Fig. 1;

Fig. 4, a view in transverse section on the line 4—4 in Fig. 1;

Fig. 5, a side view of an elementary form of die for forming the end of the exchanger tube; and

Fig. 6, a view in end elevation of the die.

Like characters of reference indicate like parts throughout the several views in the drawing.

Referring to the drawing, a tube 10 adapted to carry a refrigerant fluid is carried entirely through a length of tubing 11 of larger diameter so that the tube 10 will extend by both ends from the respective ends of the tube 11. Then in one end of the tube 11 is inserted a smaller diameter tube 12 by a short length thereof only and in the same manner the end of a small diameter tube 13 is inserted into the opposite end of the tube 11 for a short distance only.

Each end of the tube 11 is then deformed by any means, such as by the two-part die, as illustrated in Figs. 5 and 6, to press the tube 11 circumferentially around the tube 10 and thence around that part of the tube 12 inserted therewithin, causing the wall of the tube 11 then to

assume that shape as shown in cross section in Fig. 2. The die, as above indicated, is formed in the two parts 14 and 15. A hole 16 is formed therethrough and centered on the dividing line between the two die sections and a second hole 17 of smaller diameter is likewise formed therethrough and centered on the same parting line. The circumferences of the two holes intersect to leave an opening therebetween. The shoulders left on either side of this opening 18 draw the wall of the tubing 11 around in between the tube 10 and the tubes 12 and 13 when the die is placed by its two parts around the respective ends of the tube 10 and forced together with the openings 16 and 17, centering on the axes of the tube 10 and the tubes 12, 13.

Following the deformation of each end of the tube 11, the tubes 10 and 12 on the one end and 10 and 13 on the other end are then sealed one to the other by any suitable means, such as by causing metal 19 to flow within the tube 11 and around the tubes 10 and 12 and 13 by any suitable means, such as by soldering and sweating or by brazing. To facilitate the entrance of this metal, each end of the tube 11 is preferably flared outwardly into bell-shaped ends, as indicated in Fig. 1.

Thus it is to be noted that the seal around the tube 10 and the tube 12 is formed in one heating operation as is likewise the seal formed around the tube 10 and the tube 13 at the outer end of the tube 11. These ends of the tube 11 are removed one from the other at quite a distance so that the seal of one end does not affect the seal previously formed in the other end. The inwardly extending ribs 20 and 21 formed by the die in the wall of the tube 11 at each end thereof serve to mechanically space the tubes 12 and 13 from the tube 10 and also to limit the amount of metal required to form the seal. The spacing between the tube 10 and the tubes 12 and 13 within the ends of the tube 11 is somewhat exaggerated in the drawing in order to show clearly that there is a metal seal introduced between those members to effect a permanent bond therebetween and therearound.

In the heat exchanger thus formed, the medium being circulated for the absorption of or dissipation of heat is carried through the tube 10. Then the device for supplying heat to or removing heat from that medium in the tube 10 is introduced through either tube 12 or 13 and discharged within the tube 11 to circulate and flow therewithin around the tube 10 and be discharged from the other end of the tube 11 through the other smaller

diameter tube 13 or 12 as the case may be, depending upon the direction of flow. This is accomplished all without the use of the heretofore required fittings that were separately sweated first to the tube 10 and then to the tube 12 and finally to the tube 11.

Preferably the combined external diameters of the tube 10 and the tube 12 (the tube 13 being of the same external diameter as that of the tube 12) is made to approximate the internal diameter of the tube 11, being just sufficiently less to permit the easy insertion within the tube 11 of the tube 10 and the tubes 12 and 13 along thereasid. Then when the ends of the tube 11 are deformed, the major external dimension across the deformed end will still remain substantially that of the external diameter of the undeformed part of the tube 11. The tubes 10, 11, 12 and 13 are made out of suitable metal, such as copper, brass, tin, or the like as commonly employed in heat exchangers for good heat conductivity.

While I have herein shown and described my

invention in the one particular form, it is obvious that structural variations may be employed without departing from the spirit of the invention and I, therefore, do not desire to be limited to that precise form beyond the limitations as may be imposed by the following claims.

I claim:

In a heat exchanger, a length of major diameter pipe of circular cross-section having an integral end portion shaped in figure 8 cross-section defined by the pipe wall being infolded to provide two bores through said portion; a pair of pipes entered into said major diameter pipe, one through each of said bores, and one pipe continuing through the major pipe; and both of said bores having their cross-sectional areas within the internal cross-sectional area of said major pipe whereby the major dimension of said pipe end portion substantially does not exceed the diameter of said major pipe.

CLARENCE A. QUILLEN.
